DESIGN FOR A BINOCULAR OR THE LIKE

William Bausch, Rochester, and James V. Vevirit,
Lewiston, N. Y., assignors to Bausch & Lomb
Optical Company, Rochester, N. Y., a corpora-
tion of New York

Application February 27, 1942, Serial No. 166,016

Term of patent 14 years

To all whom it may concern:

Be it known that we, William Bausch and James V. Vevirit, citizens of the United States and residents of Rochester, in the county of Monroe, State of New York, and the Village of Lewiston, in the county of Niagara, State of New York, respectively, have invented a new, original, and ornamental Design for a Binocular or the like, of which the following is a specification, reference being had to the accompanying drawings, forming a part thereof.

Fig. 1 is a front view of a binocular or the like showing our new design.

Fig. 2 is a side view thereof.

Fig. 3 is a rear view thereof.

Fig. 4 is a top plan view thereof on a slightly larger scale.

The characteristic features of the design are shown in full lines on the drawings.

We claim:

The ornamental design for a binocular or the like, substantially as shown and described.

WILLIAM BAUSCH.
JAMES V. VEVIRIT.
